UNITED STATES PATENT OFFICE.

THOMAS EDGAR ADAMS, OF CLEVELAND, OHIO.

LUBRICATOR FOR COMMUTATORS.

SPECIFICATION forming part of Letters Patent No. 351,148, dated October 19, 1886.

Application filed June 22, 1886. Serial No. 205,917. (No model.)

To all whom it may concern:

Be it known that I, THOMAS EDGAR ADAMS, of Cleveland, in the county of Cuyahoga and State of Ohio, have invented certain new and useful Improvements in Lubricators for Commutators; and I do hereby declare the following to be a full, clear, and exact description of the invention, such as will enable others skilled in the art to which it appertains to make and use the same.

My invention relates to an improvement in lubricators for commutators of dynamo-electric machines.

The object is to provide a device for supplying the wearing-surface of a commutator with a lubricant, in order to prevent cutting and reduce wear from the friction of the collector-brushes which rest upon it.

With these ends in view my invention consists in certain features of construction and combinations of parts, as will be hereinafter described, and pointed out in the claims.

In the accompanying drawings, Figure 1 is a view of the lubricator attached to the collector-brush of a "Brush" dynamo. Fig. 2 is an enlarged view of the lubricator in vertical section. Fig. 3 is a plan view of the lubricator; and Figs. 4, 5, 6, and 7 represent modifications.

In illustrating the application of the lubricator to a commutator I have represented a commutator of the type known as the "Brush" commutator; but I do not wish to limit myself in its application to that type or any particular type of commutator, as its application is quite general.

The brushes A of the above-referred-to commutator are secured to a support, B, which is constructed to admit of a limited rocking motion for the purpose of adjusting the brushes in different positions on the commutator. In this type it is found preferable to attach the lubricator to some portion of the support B, in order that it may be moved simultaneously with the movement of the brushes, and thereby maintain the same position relatively thereto.

A pair of jaws, C, provided with handles c, are pivoted together, after the manner of tongs, and are adapted to slip underneath the heads D of the set-screws which secure the brush to its support. The jaws are caused to automatically grip the screw-heads, or any other part

which they may be arranged to engage, by a spring or two half-springs, E, between the handles. The jaw toward the commutator is provided with a lubricator-supporting arm, F, which preferably extends in curved form, as shown, over to a point above the side of the commutator nearest the jaw C. The arm F is made, preferably, of vulcanized fiber, in order to secure strength and lightness, and at the same time insulate the lubricator from the brush-support. To the free end of the arm F a bolt, G, is hinged, and the lubricator is constructed and attached to the bolt as follows: H represents the casing of the lubricator, which is preferably oblong in cross-section, and adapted to rest with one of its longer sides parallel with an element of surface on the face of the commutator. The top of the casing H is permanently closed, excepting an opening, h, for the introduction of a free supply of lubricant, and a central opening through which the bolt G extends, and which is closed oil-tight by a flange, g, on the bolt. The bottom of the casing H is closed by a piece of porous material, I, leather, felt, or other suitable material, which is held in position and compressed or allowed to expand by means of a nut, K, which works on the threaded end of the bolt G beneath the porous material I. One edge of the porous piece I is adapted to rest in contact with the face of the commutator L, and the degree of its pressure against the commutator is determined by a spring-arm, M, secured to the supporting-arm F, its free end resting on a projection, N, secured to the head or body of the bolt G above the casing, and hence tending to swing the lower end of the lubricator or porous piece I toward the commutator. The bearing of the edge of the piece I on the face of the commutator is so extended that there is no tendency of the piece to turn, from jar or otherwise, and hence an accidental change of feed is impossible. The interior of the casing H forms a reservoir for containing a supply of the lubricant, which, by saturating the porous piece I, is fed to the face of the commutator through the pores of the said piece I. By revolving the nut K, casing H, and porous piece I together on the bolt G the nut K will be advanced toward or caused to recede from the bottom of the casing, and the porous piece I will be thereby com-

pressed or allowed to expand and the feed of the lubricant thereby choked or rendered free, as found desirable.

Either edge of the piece I may be presented 5 to the face of the commutator, and hence a half-turn only of the nut K will be required to bring the porous feed into operative position, and, since the threads on the bolt G are cut very fine, the construction admits of the 10 nicest adjustment of the pressure on the piece I, and hence the regulation of the amount of lubricant fed to the commutator may be accomplished with the greatest precision. This 15 latter feature is very important, since the least possible amount of the lubricant to accomplish the purpose should be used, in order to prevent poor electric contact of the brushes, dirt, and flashing of the machine.

It will be observed that the above construction 20 and arrangement of the lubricator do not prevent the spark or the condition of the commutator from being readily seen, that it can be removed for cleaning, filling, or transferring to another machine without the use of 25 tools, and that it is provided with a reservoir of lubricating material, easily refilled, and of sufficient capacity to last a considerable time.

In Fig. 4 the porous piece is represented as 30 consisting of wood, the lubricant-supply being in contact with one end of the piece, and the opposite end of the piece in contact with the commutator, the oil being fed longitudinally through the pores of the wood. The casing H is made slightly bell-mouthed and the piece 35 of wood I so tightly set therein that the lubricant can only escape through the pores of the wood.

In Fig. 5 a piece of rawhide, I', or other substance adapted to sustain wear, is inserted 40 beneath the wood piece, and projects slightly beyond it, thereby relieving its end from frictional wear.

In the modification shown in Fig. 6 a piece 45 of rawhide, I', or other material capable of sustaining wear, is inserted beneath the porous piece I, of the form shown in Fig. 2, the edges of the piece I' being adapted to project a little beyond the edges of the porous piece I and protect it from wear. In this construction a 50 nut, k, is employed on the bolt G, within the casing, above the porous piece I, to press the piece I' oil-tight against the nut K, while the nut K is employed as before to compress or release the porous piece I. This latter construction is quite similar in all its essential parts to 55 the construction set forth at length hereinbefore, and may be fairly considered a somewhat more elaborate form of the principal construction, rather than a modification thereof. In this construction, as well as in the construction shown in Fig. 5, the lubricant is fed 60 to the parts I' through the porous material I.

The simple form shown in Fig. 7 consists of 65 a piece of wood or other suitable porous material set in a slot in the swinging bolt G, with its grain or pores endwise toward the commutator. In this instance the wood or other ma-

terial is to be saturated with a lubricant before being set in the bolt.

It is evident that various changes might be 70 resorted to in the means for securing the lubricator-support to the dynamo-machine or brush-support, that the shape of the casing might be of other form than those shown, and that many slight changes might be resorted to 75 in the form and arrangement of the several parts described without departing from the spirit and scope of my invention; hence I do not wish to limit myself strictly to the construction herein set forth; but,

Having fully described my invention, what I claim as new, and desire to secure by Letters Patent, is—

1. The combination, with a brush-supporting device of a dynamo-electric machine, of a 85 lubricator attached to said device and suspended in swinging adjustment, and provided with a porous feeding strip or block rigidly secured to the lubricator and adapted to feed the lubricant to the commutator, substantially 90 as set forth.

2. In a lubricator for the commutator of a dynamo-electric machine, the combination, 95 with a movable brush-support, of a lubricator attached to said support, whereby the relative position of the lubricator to the brush is maintained, substantially as set forth.

3. A lubricator suspended in swinging adjustment and provided with a spring-actuated clutch for securing it removably to a dynamo- 100 electric machine, substantially as set forth.

4. A lubricator for the commutator of a dynamo-electric machine, yielding held in contact with the commutator, and provided with a reservoir adapted to contain a supply of lubricant, substantially as set forth.

5. A lubricator for the commutator of a dynamo-electric machine, having an adjustable feed, and provided with a spring-actuated clutch for removably securing it to a dynamo- 110 electric machine, substantially as set forth.

6. In a lubricator for the commutator of a dynamo-electric machine, the combination, 115 with a reservoir suspended in swinging adjustment, of a lubricator-transmitting medium and means adapted to regulate the passage of the lubricant through the medium, substantially as set forth.

7. In a lubricator for the commutator of a dynamo-electric machine, the combination, 120 with a reservoir suspended in swinging adjustment, of a lubricator-transmitting medium, and means for applying pressure to and removing it from the medium for the purpose of regulating the passage of the lubricant 125 through the medium, substantially as set forth.

8. In a lubricator, the combination, with a reservoir and a porous feed-piece, of an auxiliary feed-piece adapted to protect the porous feed-piece from wear, substantially as set 130 forth.

9. In a lubricator, the combination, with a pair of spring-actuated jaws, and an insulating-arm leading from one of the jaws toward

the commutator, of a lubricant-receptacle hinged to the free end of the insulating-arm, substantially as set forth.

10. In a lubricator, the combination, with a suitable support, of a threaded bolt hinged to the free end of the support, a lubricant-receptacle attached to the bolt, and a lubricant-transmitting medium, substantially as set forth.

In testimony whereof I have signed this specification in the presence of two subscribing witnesses.

THOMAS EDGAR ADAMS.
